UNITED STATES PATENT OFFICE

GEORGE W. HEENE, OF CLEVELAND, OHIO

EMBOSSING AND VENDING APPARATUS

Application filed September 25, 1930. Serial No. 484,274.

My invention is an improvement in embossing and vending apparatus and relates more particularly to a die hammer and actuating mechanism therefor.

5 The present invention is particularly adapted for use with an apparatus such as is shown in my Patent No. 1,494,839, patented May 20, 1924, in which any one of a number of dies may be selected by the operator and 10 brought into proper position between a blank and the die hammer and in which suitable mechanism is provided for advancing the blank for the next impression and for simultaneously lifting the hammer to a point where 15 it may be dropped upon the selected die whereby the next impression may be made on the advanced blank.

It is an object of my invention to lift the hammer to a position where it may be 20 dropped upon a selected die for making an impression on a blank in such a manner that the downward movement of the hammer will not be interfered with even though the lifting means has not been returned to its normal 25 position for a subsequent lifting operation.

Another object of my invention is to predetermine the depth of an impression in the blank made by a selected die.

A further object of my invention is to eliminate a point of dead center between an extension of the hammer and the hammer lifting mechanism during the movement of the latter in either of its directions.

30 A still further object of my invention is to enable an operator of this apparatus to lift the hammer for a number of successive impressions without necessitating the return of the hammer lifting mechanism to one of its extreme positions.

35 Further objects and advantages of my invention will become more apparent as the following description of an embodiment progresses, reference being made to the accompanying drawing in which like reference characters are employed to designate like parts throughout the same.

In the drawing:

Figure 1 is a side elevation of an embodiment of my invention showing parts of the associated apparatus, and also showing the

hammer and operating means in raised position in broken lines.

Figure 2 is a front elevation of the hammer showing the lifting means and other parts.

55 Figure 3 is a slightly enlarged front elevation of the hammer head.

Figure 4 is a detailed top elevation of an adjustable extension or finger carried by the hammer head.

60 Figure 5 is a side elevation of the extension shown assembled in the hammer head, the latter being shown in cross-section.

65 Figure 6 is a front elevation of a portion of the hammer head showing the extension in an adjusted position and illustrating the hammer in such position that it is about to be released by the lifting mechanism.

70 Figure 7 is a view similar to that of Figure 6, except that the hammer is shown in the lowered position while the lifting means, in solid lines, is being returned to normal position. In broken lines I have indicated the position of the lifting nose after it has passed out of engagement with the hammer extension.

75 In the drawing I have illustrated the preferred embodiment of my invention as applied to an apparatus disclosed in my Patent No. 1,494,839 patented May 20, 1924. In Figures 1 and 2 I have illustrated parts of the embossing and vending apparatus with which the present invention is associated.

80 A blank 1 is seated in a rotatable chuck 2 carried in the base 3. A series of radial normally lifted dies 4 are carried on a selector shaft 5, there being suitable mechanism (not shown) for rotating the shaft in order to bring a selected die to proper position over the blank carried by the chuck. A hammer 6 is pivotally mounted at 7 on a standard 8 and terminates in an arm 9 which 85 engages a spring pressed plunger 10 carried in the casing 11.

90 The forward end of the hammer terminates in a head 12 on which is formed a die engaging face 13. Extending upwardly from the head is an enlarged portion 14 on which may be secured one or more discs 15 of different thicknesses or weights, by means of a screw or bolt 16. These discs are shown more clearly in Figure 3 and are removably attached 95 to the head 12.

to the enlarged portion 14 of the head so that the user may select discs of a predetermined weight value in determining the force of the hammer impact and the depth of the impression of the die in the blank when the hammer is released from a predetermined raised position. For instance, if a deep impression on the blank is desired all of the discs shown in Figure 3 may be secured to the head 14 to increase the weight of the hammer head. On the other hand, if a lighter impression on the blank is desired one or more of these discs may be removed so that the hammer will drop with less force to make a lighter impression on the blank.

I have provided means carried by the hammer head which may be adjusted axially and circumferentially, and which projects into the path of movement of the hammer lifting means. This adjustable means is shown more particularly in Figures 3 to 7 inclusive and is shown in detail in Figures 4 and 5. This means includes a finger or extension 17 having a main body portion and an extension 18 which is preferably semi-circular in cross-section. The end face 19 of this extension is preferably inclined upwardly toward the hammer head as shown more particularly in Figure 5.

The extension 17 is adjustable axially and circumferentially in an opening 20 formed in the hammer head and may be secured in adjusted position in the opening by means of a set screw 21. The extension 18 carries markings 22 which may be in the form of shallow grooves or depressions formed in the material of the extension and spaced at predetermined intervals. Since the member 17 is movable axially in the opening of the head, the markings 22 may be made to register with the outer face of the head to indicate to the user a predetermined axial position of the member 17 into and out of the path of movement of the hammer lifting means.

The substantially diametrical face 24 of the extension 18 is indicated more clearly in Figures 3, 6 and 7, and since the member 17 is movable circumferentially in the head the upper edge of the face 24 may be brought into register with one or more of the markings 25 on the plate 26 secured to the head by means of the screw 27. In this way a predetermined angular position of the face 24 may be obtained so that the nose of the hammer lifting means engages only a limited portion of this face during the downward movement of the lifting means when the hammer has come to rest. This is illustrated more clearly in Figure 7.

The hammer lifting means includes an operating lever 30, a shaft 31 and an arm 32. The forward end of the arm carries a nose 33 of substantial inverted U-shaped cross-section which is pivoted to the arm 32 at 34. The nose 33 is provided with a stop 35 which overlies

the end of the arm 32. If the arm 32 is moved upwardly by operating the lever 30 the forward end of the nose 33 moving in the path of the extension 18 engages the lower wall of the extension and further movement of the arm 32 will lift the hammer to the position shown in Figure 1 and more clearly in Figure 6, there being no relative movement between the nose 33 and the arm 32 during this phase of the operation. As the arm 32 approaches the position shown in Figures 5 and 6 the point 36 of the extension 18 formed by the converging walls 18 and 19, will ride over the edge of the nose as shown in Figure 5. As this point clears the nose, the hammer will drop freely and exert an impact force on the die 4 positioned over the blank 1. It will be noted that the nose 33 will not interfere with the downward movement of the hammer after it has once been released due to the inclined wall 19 which is out of the path of the nose 33.

After the hammer has dropped and is in the position shown in full lines in Figure 1 the operating lever 30 is moved in the opposite direction to drop the arm 32. This movement of the arm 32 is indicated in detail in Figure 7 and illustrates the manner in which the nose 33 engages the wall 24 of the extension 18 for only a short distance in its downward movement since this wall is set at a slight inclination to a true vertical plane. In this manner the lifting means is ready to again lift the hammer for the next impact even though it has not been returned to its extreme limit of movement in a downward direction.

Various changes may be made in the details of construction and arrangement of parts without departing from the spirit of the invention or the scope of the appended claims.

I claim:

1. In an apparatus of the class described a die actuating hammer, means to lift the hammer in position to deliver an impact blow to a die when released, and means associated with the hammer and in the path of the lifting means to regulate the lift of said hammer.

2. In an apparatus of the class described a die actuating hammer, means to lift the hammer in position to deliver an impact blow to a die when released, and means associated with the hammer and in the path of the lifting means to regulate the lift of said hammer, said last named means including an axially adjustable extension carried by the hammer.

3. In an apparatus of the class described a die actuating hammer, means to lift the hammer in position to deliver an impact blow to a die when released, and means associated with the hammer and in the path of the lifting means to regulate the lift of said hammer, said last named means including an extension adjustable axially in the hammer and having an inclined forward face for engagement

with said lifting means for a portion of its return movement, whereby the lifting means may be freely returned to normal position.

4. The combination with a die operating hammer and means for lifting said hammer to position to deliver an impact blow to a die when released, of an extension carried by the hammer extending into the path of said lifting means, said extension being adjustable axially and circumferentially in the hammer.

5. The combination with a die operating hammer and means for lifting said hammer to position to deliver an impact blow to a die when released, of an extension carried by the hammer extending into the path of said lifting means, said extension comprising a finger having a forward portion of reduced cross-sectional area and adjustable axially and circumferentially in the hammer body.

20 6. The combination with a die actuating hammer and means for lifting the hammer to deliver an impact blow to a die when released, of a finger carried by the hammer extending into the path of movement of said lifting means, said finger comprising a main body portion insertable in the hammer and an extension on an end thereof extending from said hammer, said extension being of reduced cross-sectional area with respect to the cross-sectional area of the main body portion of the finger.

25 7. The combination with a die actuating hammer and means for lifting the hammer to deliver an impact blow to a die when released, of a finger carried by the hammer extending into the path of movement of said lifting means, said finger comprising a main body portion insertable in the hammer and an extension engageable by said lifting means and of reduced cross-sectional area, having a substantially diametrically arranged face, said finger being capable of circumferential adjustment in the hammer to dispose said face at a predetermined angular position with respect to the axis of said lifting means.

30 8. The combination with a die actuating hammer and means for lifting the hammer to deliver an impact blow to a die when released, of a finger carried by the hammer extending into the path of movement of said lifting means, said finger comprising a main body portion insertable in the hammer and an extension engageable by said lifting means and of reduced cross-sectional area, having a substantially diametrically arranged face, said finger being capable of circumferential adjustment in the hammer to dispose said face at a predetermined angular position with respect to the axis of said lifting means, and indicia carried by the hammer and regulatable with an edge of said face for indicating a predetermined setting of the finger in the hammer.

35 9. In an apparatus of the class described

including a die actuating hammer means for lifting the hammer over a die, an extension engageable by the lifting means and carried by the hammer and having a face disposed in a plane substantially parallel to its axis, 70 said finger being circumferentially adjustable in the hammer to dispose the said face at a predetermined angle to the lifting means.

In testimony whereof, I hereunto affix my 75 signature.

GEORGE W. HEENE.
